PISTON FLUID PULSATATOR WITH HAND-
CONTROLLED VALVES

Johann Boerlage, Wiesbaden, Germany

Application October 23, 1930, Serial No. 490,655
In Germany July 11, 1929

1 Claim. (Cl. 230—40)

This invention relates to pulsators for medical purposes, open at the operating end and consequently single acting and intended for the simultaneous production of pressure and suction effects. Such pulsators are employed particularly for treating parts of the body under massage bells. Besides air and other gas, substances in the form of vapour or mist can be employed as actuating intermediate medium, especially for forcing medicaments into the body in a certain mist form, at the same time with the massage.

The known pulsators of this type are driven by hand or motor power and either possess coacting pressure and suction valves operated automatically by the vacuum or pressure in the pulsator or during the moving of the piston, or hand adjustable valves enabling only a shutting off or throttling of the pulsator.

According to the invention two ports extending through the cylinder walls are employed with such single acting pulsators for medical purposes with hand adjustable valves connected to the channels, one port being arranged directly in front of the surface of the piston towards the suction chamber when the piston is in its extreme suction position and the second port directly in front of the surface of the head of the other end.

It is possible by this arrangement of the pulsator, to produce, according to the desired healing purpose, both pressure impulses and also suction impulses in uninterrupted succession separately and also alternately. Moreover it is possible according to the invention, to always regulate the pressure and suction impulses to a very fine degree, as regards output and strength.

These pressure and suction impulses may, according to the invention, be produced and regulated by adjusting the valves between the individual piston strokes and also the peculiar vibrating effects produced, when, in the case of high speed for example motor driven pulsators, the valves are differently or suitably set or adjusted according to requirements and the desired effect whilst the pulsator is running. The arrangement of adjustable ports in the cylinder wall in the path traversed by the piston in the cylinder causes this effect.

The operation of the pulsator according to the invention and its advantages over ordinary suction and pressure pulsators, such as are employed for massage purposes, will be hereinafter described by way of example, with reference to the accompanying drawing in which:

Fig. 1 shows the pulsator with cylinder, partly

in section and the piston in the extreme pressure position.

Fig. 2 is a similar view, showing the piston in extreme suction position.

Fig. 3 shows a top plan view of the air pulsator with external hand adjustable valves.

In the drawing *k* represents the handle, which is hingedly connected at *i* to the piston rod *h* and oscillatable around the pivot *l*, that is, it is situated in front of the piston *e*, when this piston is in its extreme pressure position as illustrated in Fig. 1. The valve *s* controls the connection between the pulsator and the cup *r*.

The operation, due to the valve *t*, being situated with its cylinder port *w*, according to Fig. 2 directly in front of the cylinder head *y* and the valve *t*₂ with its cylinder port *w*₂ directly in front of the piston face when the piston *e* assumes the extreme suction position as shown in Fig. 2, is as follows:—

(1) By closing both valves *t*₁ and *t*₂ the air flows between the bell *r* and the piston *e* in the cylinder *d* and in the connecting tube can be accelerated alternately in opposite directions with the aid of the piston *e* reciprocated at any desired speed. Thus, positive and negative pressure impulses are produced under the bell *r* and can act as pressure and vacuum as in the known massage pulsators. In these known massage pulsators the efficiency of the massage depends, on the one hand, upon the speed of pumping or on the speed of the rotation of the motor and, on the other hand, upon the adjustment of the cock *s*, which serves for regulating the efficiency. This known effect of the massage pulsators can also be obtained with the apparatus according to the invention, when both valves *t*₁ and *t*₂ are closed as the air behind the piston *e* can always escape and flow in through the guide *m*, and as only the surface *z* of the piston *e* produces the pressure and suction impulses in the bell *r*.

(2) By completely closing the valves *t*₁ and *t*₂, illustrated in Fig. 3, and consequently the cylinder ports *w*₁ and *w*₂ during the suction stroke, a succession of strong suction strokes can be obtained, according to the invention, by hand adjustment between each stroke, without any intermediate pressure strokes, if at the termination of a suction stroke the valve *t*₁ is open and air allowed to enter slowly through the port *w*₁ in the cylinder wall for equilibrating or removing the vacuum. At the same time the piston *e* must also be moved back into the suction position according to Fig. 1, when the valve *t*₁ and consequently the port *w*₁ are closed, the air in the cylinder *d* being forced

out through the port w_1 . If the point to be massaged is very sensitive to pressure, owing to inflammation or other causes, and must be protected against pressure, the cock s is closed before re-
5 turning the piston e and again opened, when the piston has reached the position illustrated in Fig. 1, after which a fresh suction stroke can be performed. For determining the strength and intensity of the suction impulse, the piston e can
10 be drawn any desired distance into the cylinder d by means of the handle k for producing the vacuum.

(3) It is also possible to exert pressure impulses of any desired strength and intensity on
15 the portion of the body to be treated without intermediate suction impulses, if the two valves t_1 and t_2 , illustrated in Fig. 3, are maintained closed during the time, in which the piston e , according to the position shown in Fig. 2, is pushed
20 into the cylinder at any desired speed and to any desired distance with the aid of the handle k . Before pulling back the piston e the valve t_1 can be opened and the cock s closed so as to prevent a vacuum being produced under the bell r during
25 the return movement of the piston e , so that any desired sequence of only pressure stroke impulses is possible.

(4) It is also possible, by suitably controlling the working parts as described under 2 and 3, to
30 produce alternately pressure and suction impulses of any desired and varying strength and intensity, which is necessary in many instances. When effecting the suction stroke more or less air always enters the cylinder through the valve t_1 and leaves
35 same during the pressure stroke. By suitably adjusting the valve t_1 between and during the pressure and suction strokes, the suction stroke or the pressure stroke can be made weaker.

(5) By closing the valve t_1 and opening the
40 valve t_2 , strong pressures and suction strokes can be imparted successively, because at the end of the suction stroke the surface z of the piston e in the position according to Fig. 2 draws in air through the port w_2 of the open valve and each time more or less relieves the vacuum produced in
45 the cylinder d and under the bell r . The effect

of these alternating pressure and suction impulses is entirely different to the action of the pulsator as described under 1, wherein the two valves t_1 and t_2 are closed. By suitably adjusting the valve t_2 in conjunction with the speed of movement of the piston e or of the motor drive, a very accurate adjustment of the strength and intensity of the pressure and suction strokes is attained so that, by suitably adjusting the valve t_2 during the working of the pulsator or between the individual strokes, the physician can produce a very fine adjustment of the pulsator effect and consequently of the vibration effect.

(6) By opening the two valves t_1 and t_2 the suction strokes can be rendered practically ineffective, and by occasionally closing the valve t_1 the pressure impulses can be made as effective as desired.

(7) It is not necessary, as assumed under 6, to adjust the valves t_1 and t_2 , especially the valve t_1 between each suction and pressure stroke, but with a little practice it is possible, especially with a motor driven pulsator, to regulate and adjust the massage effect or the production of suction and pressure impulses by adjusting the valves
95 t_1 and t_2 whilst the pulsator is running, so that very peculiar vibration effects are produced.

I claim:

A single acting pulsator for medical purposes, comprising in combination a cylinder having two ports, a head on one end of said cylinder having a port, a cover on the other end of said cylinder, a piston adapted to be reciprocated in said cylinder, one of the ports in said cylinder being arranged in the cylinder wall at a distance from said piston cover equal to the thickness of said cylinder and the second port in said cylinder wall directly adjacent said cylinder head, means for reciprocating said piston in said cylinder, two hand controlled valves one arranged in each port of said cylinder, and a controlled valve in the port in said cylinder head, said valves adapted, according to their setting, to control the pulsator to impart suction or alternately suction and pressure impulses.
